US00D732896S

(12) **United States Design Patent**
Ludeman et al.

(10) **Patent No.:** US D732,896 S
(45) **Date of Patent:** ** Jun. 30, 2015

(54) **DISH**

(71) Applicant: **WKI Holding Company, Inc.**,
Rosemont, IL (US)

(72) Inventors: **Karl Ludeman**, Chicago, IL (US);
HuaDong Zhang, Shenzhen (CN)

(73) Assignee: **WKI Holding Company, Inc.**,
Rosemont, IL (US)

(**) Term: **14 Years**

(21) Appl. No.: **29/437,521**

(22) Filed: **Nov. 16, 2012**

(51) LOC (10) Cl. **07-01**

(52) U.S. Cl.

USPC **D7/545**

(58) **Field of Classification Search**

USPC D7/545, 543, 500, 586, 570, 560;
220/751, 23.4, 574

See application file for complete search history.

(57) **CLAIM**

We claim the ornamental design for a dish, as shown and described.

DESCRIPTION

FIG. 1 is a top perspective view of a dish according to the new design;

FIG. 2 is a bottom perspective view of the dish shown in FIG. 1;

FIG. 3 is a top view of the dish shown in FIG. 1;

FIG. 4 is a bottom view of the dish shown in FIG. 1;

FIG. 5 is a side elevation view of the dish shown in FIG. 1;

FIG. 6 is a side elevation view of the dish shown in FIG. 1;

FIG. 7 is a left end view of the dish shown in FIG. 1;

FIG. 8 is a right end view of the dish shown in FIG. 1; and,

FIG. 9 is a cross-sectional view taken along the line 9-9 of the dish shown in FIG. 7.

Features shown in broken lines form no part of the claimed design.

1 Claim, 6 Drawing Sheets
